CENTRIFUGAL SEPARATOR

The present invention relates to improvements in centrifugal separators for separating a solid-liquid mixture in a separator bowl rotating about a vertical axis.

In separators of this type, the bowl rotates at considerable speed, which often produces vibrations even if the weight of the machine parts is in proper equilibrium. Such vibrations may be caused, for instance, by non-uniform distribution of the material on the filter screen mounted on the separator bowl, particularly if such material is highly viscous and/or if the screen becomes partly displaced in the bowl.

10 Imbalances are generally found at the geometric center of gravity of the interior surface of the bowl. While elastic supports have been proposed in centrifugal separators between the rotating and fixed parts of the machine or between the machine and the foundation on which it rests, the forces of imbalance in the conventional separators are in a plane above the center of gravity of the elastically suspended or supported mass, thus producing vibrations which are transmitted to the foundation on which the machine rests, despite the elastic support means.

15 It is the primary object of this invention to overcome this disadvantage by so assembling the elastically supported parts of the machine that the center of gravity of the suspended parts approaches as closely as possible the geometrical center of gravity of the interior surface of the separator bowl, and to suspend the parts elastically at that level, while at the same time assuring a more uniform distribution of the material to be separated in the separator bowl, thus reducing the forces of imbalance during the separating operation.

20 This and other objects of the invention are accomplished in a centrifugal separator which comprises a housing including an upper portion, a fixedly supported lower portion, and an elastic support means resiliently supporting the upper housing portion of the separator on the lower separator housing portion. A vertically extending pivot in the housing is supported by the upper separator housing portion. A separating bowl having a hub is mounted for rotation on and about the pivot, the pivot extending into the interior of the bowl. The upper separator housing portion and all elements carried thereby, including the pivot and the bowl, have a center of gravity, and the elastic support means is positioned approximately at the level of the center of gravity. A screen is mounted over the interior surface of the bowl and spaced therefrom, the bowl and the screen being frusto-conical, and the elastic support means is positioned approximately at the level of the geometric center of gravity of the interior surface of the frusto-conical bowl, in the embodiment of the invention described and illustrated herein.

25 Due to this construction and distribution of weight and forces, the elastically suspended or supported part of the separator is subjected practically only to horizontal vibrations. If the elastic characteristics of the suspension means, such as rubber blocks or a rubber ring interposed between the upper and lower separator housing portions, are properly chosen, the machine may be insulated from vibrations, the vibrations of the elastic suspension means being opposite in phase to the forces of imbalance.

30 To bring the center of gravity of the suspended machine parts approximately to the level of the

geometrical center of gravity of the interior surface of the bowl, it may be necessary to make the upper portions of the upper housing portion somewhat heavier. This may be effected by increasing the thickness of the upper wall portion of the upper housing portion and/or by attaching an additional mass thereto.

35 The more even distribution of the material charged into the separator bowl is assured with a feed assembly which includes a feed pipe having an outlet end, the feed pipe being supported on the housing cover, a conical element fixed to the top of the bowl hub, the outlet end of the feed pipe being in registry with the conical element to deliver the material to this element, and a turbine wheel having radially extending blades fixed to the conical element. The blades define spaces therebetween concentrically surrounding the conical element and receiving the material from the conical element, and an outwardly flaring tube is fixed to the turbine wheel and surrounds the hub. An annular chamber is defined between the tube and hub for receiving the material from the spaces between the turbine wheel blades, the lower end of the tube defines with the bottom of the bowl a circular delivery opening means for delivering the material to the bowl, and the upper end of the tube surrounds the outlet end of the feed pipe.

40 A tight joint is provided between the upper tube end and the feed pipe outlet end to prevent the turbine wheel from acting like a ventilator and producing significant air circulation in the interior of the bowl.

45 The above and other objects, advantages and features of the present invention will become more apparent in the following detailed description of certain preferred embodiments thereof, taken in conjunction with the accompanying drawing wherein

50 FIG. 1 is a side view, largely in section, of a centrifugal separator according to this invention;

55 FIG. 2 is a side view of a small portion of the separator showing a modified suspension means; and

60 FIG. 3 is an enlarged sectional view showing modified feed assembly for the separator.

Referring now to the drawing and first to FIG. 1, there is shown a centrifugal separator comprising a frusto-conical or funnel-shaped bowl or basket 10 having an imperforate wall. A similarly funnel-shaped screen or sieve 12 is mounted in the bowl 10 spaced from the bowl wall so that an annular space is defined between the bowl wall and the screen for receiving liquid filtered through the screen during operation of the separator. This liquid is upwardly displaced during rotation of the bowl towards discharge lip 10a of the bowl. A frusto-conical skirt 14 having an imperforate wall is mounted on the discharge lip of the bowl so as to receive liquid passed outwardly through a series of apertures or an annular slot on the circumference of the discharge lip, the discharge liquid running downwardly on the skirt 14 into annular reservoir 16 constituted by sleeve 18 surrounding the bowl 10.

65 The upper rim of sleeve 18 extends close to the discharge lip of the separator bowl and a bottom wall 20 closes off the reservoir 16 whence liquid is discharged through pipe 31 passing outwardly through the walls of hopper 29. The sleeve 18 is fixed by brackets or braces 19, to the fixed upper portion of the separator housing, and brackets or braces 21 to annular support 37.

The upper portion of the separator housing is constituted by a thick-walled top cylinder 22 and downwardly extending thin-walled skirt 24 overlapping the cylindrical lower portion 28 of the separator housing. As shown, a base 33 extends radially outwardly from the lower portion of the separator housing to mount the lower separator housing portion rigidly on the foundation 29 which supports the separator. The solid material separated from the liquid in the centrifugal separator is discharged through hopper 29 which extends downwardly from the separator housing and is flanged to the lower end of the lower separator housing portion.

The upper separator housing portion is resiliently mounted on the lower separator housing portion in the following manner:

Support frameworks 27 are fixedly mounted on, or are integral with, the wall of the lower separator housing portion 28 and/or the base 33, and these supports 27 carry elastic or resilient blocks 26, for instance of rubber, which support the upper separator housing portion, brackets 23 extending radially outwardly from the thick-walled top cylinder 22 to rest on the resilient blocks 26. These blocks are positioned at the level of the center of gravity G of the suspended upper portion of the separator.

The interior of the separator housing is sealed from the atmosphere by means of suitable sealing means, such as an annular gasket 30 or a bellows sealing the joint between the upper and lower portions of the housing.

The bowl 10 rotates about the vertical pivot 34 whose axial bore houses the drive shaft 44. An annular rim 35 reinforced by radial ribs 39 extends from the lower or interior end of the pivot 34 into engagement with an annular support flange 36 which extends radially inwardly from sleeve 37. The pivot extends from its lower end outside the bowl 10 into the bowl where it carries the hub 38 on anti-friction bearings 40 and 42, the bowl 10 being fixedly connected to the hub 38.

The hub 38 is bolted or otherwise fixed to the upper end of the drive shaft 44 whose lower end carries drive pulley 43 connected by belt 41 to pulley 45 of motor 46, which is mounted on base 33 and drives shaft 44 and bowl 10.

As more clearly shown in the enlarged view of FIG. 3, a conical element 48 is fixed to the top of hub 38 in registry with the outlet of a feed conduit 50 mounted on the cover 32 of the separator housing. The conical element 48 forms the hub of a turbine wheel 52 whose radially extending blades carry an outwardly flaring tube 54 whose upper rim surrounds the outlet opening or nozzle of pipe 50. The tube extends towards the bottom of the separator bowl 10, defining with hub 38 an annular feed chamber 56, a circular discharge slot being formed between the lower rim of the tube 54 and the bottom of the separator bowl.

As will be apparent from the above description, the resiliently suspended upper portion of the centrifugal separator consists of the cylindrical housing portion 22, 24, the cover 32, which is supported on the thick-walled cylinder 22, and the feed pipe means carried by the cover, the support elements for the pivot 34, which includes the sleeve 18, the brackets or braces 19, 21 mounting the sleeve on the housing wall 22, 24 and the sleeve 37, with the support flange 36, the drive shaft

44, the bowl 10 and its hub 38, and the screen 12. In this structure, wherein the lower portion of the separator is fixed and the vertical pivot about which the bowl rotates extends into the bowl, the center of gravity G of the suspended mass of the separator is considerably higher than in conventional apparatus of this type. The thickness of the upper wall portion 22 of the separator housing is so chosen or additional material is attached thereto so that the center of gravity of the entire suspended mass is about at the same level as the geometric center of gravity of the interior surface of the bowl. Since the forces of imbalance due to a non-uniform distribution of the charge in the bowl are generally situated at this level, no tilting moment is exerted upon the suspended portion of the separator and the vibratory movements are solely horizontal.

Furthermore, the axis of rotation of the bowl is displaced parallel to itself during such vibrations, so that no tilting movement would appear unless the pivot 34 were bent. Since the latter is rigid, however, any such tilt would at most be very slight.

The suspension blocks 26, which are positioned at the level of the center of gravity of the suspended mass, are subject only to vibrations in this plane. The elasticity and absorption or damping characteristics of these support blocks are so chosen as to provide an insulation against vibration.

FIG. 2 shows a modified suspension means in which the elastic suspension blocks are replaced by a rubber ring 60 of suitable elasticity and damping characteristics. In this modification, the thick-walled cylinder wall 22' of the upper portion of the separator housing and the cylinder wall 28' of the lower separator housing portion have facing annular rims 22a and 28a, respectively, which define mating grooves receiving the rubber ring 60. In this way, the suspension ring 60 simultaneously serves as a sealing means or gasket for the joint of the separator housing portions.

The centrifugal separator hereinabove described and herein illustrated operates as follows:

A liquid-solid mixture is charged into bowl 10 through the feed pipe 50, passing outwardly between the blades of the turbine wheel 52 through the opening between the outlet end of the pipe 50 and the conical hub of the turbine wheel. Since the conical hub 48 is fixed on, or integral with, the hub 38 of the bowl 10, it turns at high speed with the bowl when the motor 46 is actuated to drive shaft 44. The liquid-solid mixture charged into the separator through pipe 50 is thus entrained by friction and begins to rotate with the conical element 48. Under centrifugal force, the charge will leave the feed pipe in a horizontal layer and will be distributed at the speed of rotation of the bowl. The turbine blades are helically inclined so as to direct the charged mixture downwardly into the tube 54 where it passes through chamber 56 and outwardly into the bowl through the circular slot defined between the lower rim of the tube 54 and the bottom of the bowl. The conical element 48 and the turbine wheel blades divide the jet of material entering the separator into several layers, which is essential for a uniform distribution of the material in the tube 54 under centrifugal action in case the material is very viscous. The material forms a continuous layer of uniform thickness on the wall of tube 54 under centrifugal force, and this layer of

material is discharged at the bottom of the tube and is thrown against the screen 12 where it is upwardly displaced by the centrifugal force. The liquid phase of the mixture is filtered through the screen and moves upwardly in the annular chamber between the screen and the imperforate wall of the bowl to be discharged through lip 10a into the reservoir 16. The solid phase of the mixture is equally displaced upwardly on the screen 12, finally passing over the upper edge of the screen into the separator housing where it is discharged by gravity into hopper 29.

The specific feed system herein described permits a particularly uniform distribution of the charged material over the whole surface of the screen, thus reducing vibrations due to forces of imbalance.

In the modification of the feed system shown in FIG. 3, the feed pipe 50' does not have an inwardly flaring outlet nozzle, as illustrated in FIG. 1, but the diameter of the feed pipe is greater than that of the material being fed so that the same freely falls onto the conical element 48. The feed pipe 50' is mounted on the tube 54 by a joint constituted by a pair of horizontal flanges 62 and 64 respectively fixed to the pipe 50' and the tube 54. The vertical position of the feed pipe is adjustable by wedge 66 positioned between the housing cover 32 and a flange 65 on the feed pipe to maintain a small gap between the flanges 62 and 64. This gap and the thickness of the flanges are so chosen as to avoid too strong an air circulation in the interior of the bowl because of the suction produced by the turbine wheel 52 which operates like a ventilator. This joint may be replaced by a labyrinth joint or any other suitable joint of conventional design serving the same purpose.

It should also be noted that, while the invention has been illustrated in connection with a frusto-conical bowl with an imperforate wall, it is obviously applicable to centrifugal separators with perforated baskets and with cylindrical rotating bowls. Other modifications may readily occur to those skilled in the art without departing from the spirit and scope of the present invention.

I claim:

1. A centrifugal separator comprising
  1. a housing, the housing including
    - a. an upper portion,
    - b. a fixedly supported lower portion, and
    - c. an elastic support means resiliently supporting the upper housing portion of the separator on the lower separator housing portion;
  2. a vertically extending pivot in said housing,
    - d. the pivot being carried by the upper separator housing portion; and
  3. a separating bowl having a hub mounted for rotation

on and about said pivot and carried thereby;

- e. the pivot extending into the interior of the bowl,
- f. the upper separator housing portion and all elements carried thereby, including the pivot and the bowl, having a center of gravity, and
- g. the elastic support means being positioned approximately at the level of the center of gravity.

5 2. The centrifugal separator of claim 1, further including a screen mounted over the interior surface of the bowl and spaced therefrom.

10 3. The centrifugal separator of claim 2, wherein the bowl and the screen are frusto-conical, and the elastic support means is positioned approximately at the level of the geometric center of gravity of the interior surface of the frusto-conical bowl.

15 4. The centrifugal separator of claim 1, further comprising a cover on the housing and a feed assembly for delivering material to be separated to the bowl, the feed assembly including a feed pipe having an outlet end, the feed pipe being supported on the housing cover, a conical element fixed to the top of the bowl hub, the outlet end of the feed pipe being in registry with the conical element to deliver the material to said element, a turbine wheel having radially extending

20 blades fixed to the conical element, the blades defining spaces therebetween concentrically surrounding the conical element and receiving the material from the conical element, an outwardly flaring tube fixed to the turbine wheel and surrounding the hub, an annular

25 chamber being defined between the tube and the hub for receiving the material from said spaces, the lower end of the tube defining with the bottom of the bowl a circular delivery opening means for delivering the material to the bowl, and the upper end of the tube surrounding the outlet end of the feed pipe.

30 5. The centrifugal separator of claim 4, further comprising a joint between the upper end of the tube and the outlet end of the feed pipe.

35 6. The centrifugal separator of claim 1, wherein the upper housing portion comprises an upper and a lower wall portion, the thickness of the upper wall portion exceeding that of the lower wall portion.

40 7. The centrifugal separator of claim 1, wherein the elastic support means comprises blocks of elastic material.

45 8. The centrifugal separator of claim 1, wherein the elastic support means comprises a ring of elastic material mounted between the upper and lower separator housing portions.

50 9. The centrifugal separator of claim 1, further comprising a tight joint between the upper and lower separator housing portions.
